Primary Examiner — Cynthia M. Chin(74) *Attorney, Agent, or Firm* — Sterne, Kessler,
Goldstein & Fox PLLC.(57) **CLAIM**

The ornamental design for a toy building block, as shown and described.

DESCRIPTION

FIG. 1 is a front left perspective view of a toy building block showing the claimed design;

FIG. 2 is a front right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets*FIG. 1*

FIG. 2

FIG. 3

FIG. 4

FIG. 5

FIG. 6

FIG. 7

FIG. 8
